UNITED STATES PATENT OFFICE.

DAVID A. BACKUS, OF GROTON, NEW YORK.

GARMENT-SUPPORTER.

SPECIFICATION forming part of Letters Patent No. 624,441, dated May 9, 1899.

Application filed April 28, 1898. Serial No. 679,127. (No model.)

To all whom it may concern:

Be it known that I, DAVID A. BACKUS, a citizen of the United States, residing at Groton, in the county of Tompkins and State of New York, have invented certain new and useful Improvements in Garment-Supporters; and I do hereby declare the following to be a full, clear, and exact description of the invention, such as will enable others skilled in the art to 10 which it appertains to make and use the same.

The object of the present invention is the provision of a lady's garment-supporter of novel construction which will be adapted for supporting both the hose and skirts in such 15 an improved manner that the device will perform its functions most satisfactorily without any discomfort to the wearer.

The foregoing and other objects of the invention are accomplished by the provision of 20 improved hose-supporters in connection with a novel form of bustle and improved suspenders whereby the weight of the garments is borne by the shoulders of the wearer, all 25 of said elements being of a detailed construction and coacting in the improved manner more fully set forth hereinafter.

In the accompanying drawings, Figure 1 is a view showing the device in use, and Fig. 2 a perspective detail view of the complete invention.

An arc-shaped ribbon 1, of steel or other resilient material, constitutes the frame of the bustle, and 2 is a cross band or piece of webbing which extends from one extremity 35 of this member to the other extremity thereof and is looped upwardly to a certain extent at the points where buckles 3 and 4 are connected to it, said cross-band being adapted to rest against the body of the wearer, so 40 as to form a support for the bustle at the point of contact of the bustle portion of the supporter. A pair of suspenders consisting of two loops 5 and 6 is employed, and the outer pieces of said suspenders are engaged 45 with the buckles 3 and 4, so that the size of the loops can be varied, while the vertical back or center piece of the suspenders is connected to the central part of the cross-band 2 at 7 and is then extended into a horizontal 50 portion 8, which is fastened to the center part of the resilient ribbon 1 at 9. There are two

adjusting straps or bands 10 and 11, each having one end connected to an extremity of the resilient frame 1, and their inner free ends are adjustably connected to the portion 8 of 55 the center piece of the suspenders, independent buckles 12 being employed at these points. Hose-suspending bands 13 and 14, of elastic material, which are prolongations of the cross-band 2, depend from the extremities of the 60 frame 1, and branch straps 15 and 16, having the usual hose-fasteners 17, are adjustably connected to the elastic suspending-bands by respective buckles 18 and 19.

In placing the device on the person the arms 65 are slipped through the loops 5 and 6 and the suspending-bands 13 and 14 brought over the hips and connected to the front portions of the hose. It is clear that the weight of both skirts and hose is borne by the shoulders, which is decidedly advantageous, and quick and easy adjustment of all the parts can be had, when necessary, so that the device will properly fit the wearer and be perfectly comfortable. The adjusting-straps 10 70 and 11 afford means for regulating the size and shape of the frame 1, so that the bustle 75 can be made to suit the requirements of the occasion.

Having thus described my invention, what 80 I claim as new, and desire to secure by Letters Patent, is—

In a garment-supporter, a band or ribbon of resilient material, a cross-band connecting the ends thereof and having its ends extended to form hose-supports, looped bands adjustably secured to said cross-band between the ends of the ribbon and being also connected together to form a back or center piece which is secured to the middle points 85 of the cross-band and the ribbon and independent adjusting-bands connecting the ends of the ribbon to that portion of the center band which is between the cross-band and the ribbon, substantially as described. 90

In testimony whereof I affix my signature in presence of two witnesses.

DAVID A. BACKUS.
